US0D1108620S

(12) **United States Design Patent** (10) **Patent No.:** **US D1,108,620 S**
(45) **Date of Patent:** **** Jan. 6, 2026**

(54) **CEILING FAN LIGHT KIT**

(71) Applicant: **Hunter Fan Company**, Memphis, TN (US)

(72) Inventor: **Alexander Jonathan Haggard**, Memphis, TN (US)

(73) Assignee: **Hunter Fan Company**, Memphis, TN (US)

(**) Term: **15 Years**

(21) Appl. No.: **29/866,186**

(22) Filed: **Aug. 31, 2022**

Related U.S. Application Data

(62) Division of application No. 29/751,128, filed on Sep. 18, 2020, now Pat. No. Des. 966,493, which is a division of application No. 29/624,826, filed on Nov. 3, 2017, now Pat. No. Des. 874,634.

(57) **CLAIM**

The ornamental design for a ceiling fan light kit as shown and described.

DESCRIPTION

FIG. 1 is a bottom perspective view of a ceiling fan light kit shown in the environment of the ceiling fan;
FIG. 2 is a top perspective view of the ceiling fan light kit of FIG. 1;

FIG. 3 is a top view of the ceiling fan light kit of FIG. 1;
FIG. 4 is a bottom view of the ceiling fan light kit of FIG. 1;

FIG. 5 is a side view of the ceiling fan light kit of FIG. 1;
FIG. 6 is a bottom perspective view of an alternative ceiling fan light kit shown in the environment of the ceiling fan;
FIG. 7 is a top perspective view of the ceiling fan light kit of FIG. 6;

FIG. 8 is a top view of the ceiling fan light kit of FIG. 6;
FIG. 9 is a bottom view of the ceiling fan light kit of FIG. 6; and,

FIG. 10 is a side view of the ceiling fan light kit of FIG. 6. The broken lines illustrate portions of the ceiling fan light kit and ceiling fan environment. None of the broken lines form part of the claimed design.

1 Claim, 10 Drawing Sheets
